assignor to Electric & Musical Industries Limited,
Hayes, Middlesex, England, a company of
Great Britain

Application April 22, 1939, Serial No. 269,397
In Great Britain April 25, 1938

4 Claims. (Cl. 256—36)

The present invention relates to thermionic valve circuits.

It is an object of the present invention to provide improved means for the mixing of electrical signals. An additional object of the invention is to provide improved means for the production of pulses such, for example, as are required in television systems.

According to one feature of the invention a thermionic valve circuit for mixing electrical signals is provided comprising two or more thermionic valves having their cathodes connected together and provided with a common cathode impedance, a set of electrical signals and means for applying said signals to the control electrode of one of said valves and a second set of electrical signals for mixing with the first mentioned set of signals, and means for applying the second mentioned set of signals to the control electrode of another of said valves, the application of a set of signals to one of said valves causing, or tending to cause the cathode potential of said valve to vary and thus producing, or tending to produce, potential variations across said impedance, which potential variations are applied effectively between the cathode and the control electrode of another valve so that the sets of signals applied individually to said valves are effectively mixed and appear as mixed signals in one or more of the anode circuits of said valves and wherein, in order to limit the amplitude of signals passed by any of said valves it is arranged that on the application to one of said valves of signals having positive values exceeding a predetermined value beyond which limitation is required, the control electrode-cathode potential of another of said valves is brought to a point where the amplification of that valve is reduced or eliminated.

In one form of the invention, the circuit comprises two thermionic valves, and signals to be mixed are applied to the two control electrodes of said valves, and the mixed signals are derived from either anode circuit of said valves or in push-pull from both anode circuits.

According to another feature of the invention, a thermionic valve circuit for the generation of pulses is provided comprising a pair of thermionic valves having their cathodes connected together and provided with a common cathode impedance, a source of controlling signal pulses having sharp leading edges and means for applying said pulses to one of said valves so to cause that valve to be rendered conducting or non-conducting and the other valve substantially

non-conducting or conducting, and means for applying to the other valve controlling signal pulses also having sharp leading edges and having a time relationship with the first mentioned pulses so as to cause the last mentioned valve to be rendered conducting or non-conducting and the previously conducting or non-conducting valve substantially non-conducting or conducting, the arrangement serving to generate pulses having a duration substantially equal to the time interval between the pulses applied to the respective valves.

The arrangement according to this feature of the invention may be employed for measuring the time or phase relationship between two sets of pulses, the measure of the time or phase relationship being a function of the duration of the pulses generated by the circuit. This feature of the invention may also be employed for generating pulses of a predetermined duration. In this case the two sets of controlling pulses are arranged to have a predetermined time relationship and preferably a single source of controlling pulses is employed and the predetermined time relationship is obtained by the provision of time delay means.

In order that the said invention may be clearly understood and readily carried into effect the same will now be more fully described with reference to the accompanying drawing in which—

Figure 1 is a circuit arrangement for mixing two sets of electrical signals and

Figure 2 is a circuit arrangement for the generation of pulses.

Figure 1 shows two tetrode valves 11 and 12 with their cathodes joined together and connected to an impedance 13 (shown as a resistance) which is connected to a source of negative potential. It is preferable that the value of the impedance 13 at all frequencies it is desired to mix is large compared with reciprocal of the mutual conductive of the valves 11 and 12, but this is not absolutely necessary if push-pull signals are not desired. One set of signals is applied to the input terminal 16 which is connected via a coupling condenser to the grid of valve 11 which has a suitable grid leak resistance. The set of signals to be mixed with the signals applied to terminal 16 is applied to the input terminal 17 which is connected via a coupling condenser to the grid of valve 12, also having a leak resistance. Positive potentials are applied to the screening grids of the tetrodes 11 and 12 in the usual manner, and the biases on the control grids are arranged so that the valves

operate on substantially linear portions of their characteristics. The anodes of the valves are connected through separate anode impedances (shown as resistances) to suitable positive potentials and to output terminals 14 and 15. If a varying potential is applied to the terminal 16 the cathode potential of valve 11 tends to follow the potential of the grid of valve 11. Similarly the cathode potential of valve 12 tends to follow the potential of the grid of valve 12. Assuming the potential applied to terminal 16 to be V_1 volts, and the potential applied to terminal 17 to be V_2 volts, then the anode current change in one of the valves can be shown to be approximately $(V_1 - V_2) g/2$, where g is the mutual conductance of one valve, it being assumed that the valves are working on the linear portions of their characteristics and that the cathode impedance 13 is large compared with the reciprocal of g . The signals applied at 16 and 17 are therefore mixed and the mixed output may be taken off at 14 or 15, or at both in push pull. Provided that the current in the impedance 13 is less than that passed by either valve at zero grid bias an excessive input to either 16 or 17 will not cause grid current to flow, but will cause a limited output signal in one or other direction the whole of the current through 13 flowing through one of the valves. As the output depends on the difference of the potentials applied to the grids at 16 and 17, the inputs are relatively reversed in phase before mixing. It will be apparent that more than two valves may be used in such a mixing circuit where more than two signals are required to be mixed. For example for mixing three signals three valves may have their cathodes joined to a common cathode resistance, the mixture being obtained in any of the anode circuits of the valves.

Figure 2 shows a circuit for the production of a short pulse from longer controlling pulses which is a modification of Figure 1. Parts in Figure 2 which correspond to similar parts in Figure 1 have been given the same reference numerals. The terminal 19 represents the input terminal to the grid of a valve 20, which acts as a "cathode follower" valve, the resistance 21, delay network 18 and terminating resistance 22 acting as the cathode impedance. The input terminals 16 and 17 of the two valves 11 and 12 are connected to tappings on the delay network, which comprises series inductances and shunt capacitances connected in the normal manner. The purpose of the resistance 21 together with the cathode impedance of the valve 20 is to terminate correctly the delay network at the input end. The anode of valve 20 is connected to a source of positive potential. The valves 11 and 12 are triodes and the grid of valve 11 is biased negatively by a battery 23 and the grid of valve 12 is biased positively by a battery 24.

In order to explain the operation of the circuit of Figure 2 it will be assumed, for example, that it is necessary to produce so called line synchronising pulses for television purposes, the pulses being of, say, 10 micro-seconds duration. Positive controlling pulses of longer duration than 10 micro-seconds, which pulses may, for example, be line sawtooth waves (i. e. saw-tooth wave-forms occurring at line frequency) with a rapid stroke at the beginning of each saw-tooth wave are applied to terminal 19, and the pulses then travel along the delay network. The terminals 16 and 17 are tapped on the delay network

18 at points 10 micro-seconds apart. The biases on the valves are arranged so that normally with no signal input the valve 11 is non-conducting and valve 12 is conducting. When the positive 5 rapid leading edge of the saw-tooth arrives at the grid of valve 11 it switches valve 11 on and therefore renders valve 12 non-conducting. When the leading edge arrives at the grid of valve 12 it switches this valve on and automatically switches off valve 11. Thus a short pulse of 10 micro-seconds duration is produced. Actually a negative pulse is obtained at 14 and a positive pulse is obtained at 15. The edges of the short pulse are determined by the leading 10 edge of the waveform applied at terminal 19. After the leading edge has arrived at 17 and turned off valve 11, the trailing edge of the saw-tooth wave form will only bias valve 11 more negatively thus maintaining it in the off position. Hence only the leading edge of the wave-form 15 applied at terminal 19 is of importance, provided that there is an interval in excess of (in the present example) 10 micro-seconds between the end of the pulse and the beginning of the next. As an example of the operation of a circuit such as Figure 2 suppose the resistance 13 passes 10 milliamperes and valves 11 and 12 are such that they require -2 volts between grid and cathode in order to cause 10 m.a. to flow and -12 volts to cut off the anode current. If the grid of valve 11 is -12 volts with respect to its cathode and the grid of valve 12 is -2 volts with respect to its cathode, then valve 12 will pass 10 m.a. and valve 11 will pass no current. A potential difference of 10 volts applied between the two grids (in such a sense as to bias valve 12 more negatively) will cause valve 11 to pass 10 m.a. and valve 12 to pass no current. In practice in order to allow for variation in valve characteristics the grid bias of valve 11 is made, say, 15 volts negative of the grid bias of valve 12 so as to allow 20 5 volts tolerance. If the input at 16 be 30 volts, then the leading edge will drive the grid of valve 11 to 15 volts more positive than the grid of valve 12 thus producing a pulse which is limited in amplitude in the anode circuit of valve 12.

The valves 11 and 12 in Figure 2 have been shown as triodes though, of course, pentodes or tetrodes may be used. With the triodes the anode-grid capacities of the valves may be neutralised if desired by cross coupled condensers from the anodes to the grids of the valves. A slight over neutralisation will tend to sharpen the pulse output. As the valves are not working linearly irregularities may be produced by such neutralisation at the beginning and end of pulses so that screened valves are often preferable. The operation of Figure 2 has been described with reference to a control wave which has a sharp leading edge rising positively. The arrangement may be equally well used with a negative sharp leading edge. In this latter case the biases of the valves are interchanged, valve 11 being normally conducting and valve 12 normally non-conducting. The negative pulse switches off valve 11 first (thus switching on 12) and then switches off valve 12 restoring the circuit to its original condition.

The arrangement of Figure 2 may be used with other pairs of valves to produce other pulses from the same delay network. Tappings for the other valves are taken from suitable places on the network to obtain the desired start and stop times for the pulses.

A pair of valves as shown in Figure 1 may be

used to mix pulses, such as those derived from apparatus as shown in Figure 2, say, frame frequency pulses. For example, the grid of valve 11 (in Figure 1) may be biased more negatively than the grid of valve 12, so that valve 11 is normally cut off. Positive line frequency pulses (as derived from terminal 15 in Figure 2) are applied to terminal 16 with sufficient amplitude to turn valve 11 on and valve 12 off. Negative frame frequency pulses (derived, for example, by an arrangement such as Figure 2 with frame frequency control pulses and a longer delay period) are applied to terminal 17 and are of sufficient amplitude to switch valve 12 off and valve 11 on (as for line pulses). The simultaneous occurrence of line and frame pulses gives an output signal at 14 or 15 of substantially the same amplitude as that given by either alone.

I claim:

1. Apparatus for producing a wave form of definite duration comprising a pair of thermionic tubes having anode, cathode and at least one control electrode, said cathodes being electrically connected together, impedance means connected to said cathodes and common to the anode-cathode path of both of said tubes, a variable delay network, means connecting the control electrode of each of said tubes to a point on said delay network, and means for impressing an electric wave onto said delay network.

2. Apparatus in accordance with claim 1, wherein there is provided in addition an additional thermionic vacuum tube having anode,

cathode and at least one control electrode, and having said time delay network connected in the anode-cathode path thereof as a cathode impedance.

5. Apparatus for combining a plurality of electric waves comprising at least two thermionic tubes, each having an anode, cathode, and at least one control electrode, said cathodes being electrically connected together, impedance means common to the control electrode-cathode paths and anode-cathode paths of said tubes, means for impressing one of said waves on the control electrode-cathode path of one of said tubes, means for impressing another of said waves on the control electrode-cathode path of the other of said tubes, an impedance means connected in the anode-cathode path of each of said tubes, and means for deriving push-pull waves from said combined waves comprising output terminal means connected to each of said impedance means.

20 25 30 4. Apparatus for producing a wave form of definite duration comprising a pair of thermionic tubes having anode, cathode and at least one control electrode, said cathodes being electrically connected together, impedance means connected to said cathodes and common to the anode-cathode path of both of said tubes, a delay network, means connecting the control electrode of each of said tubes to a point on said delay network, and means for impressing an electric wave onto said delay network.
